CLAIM

The ornamental design for a lid as shown and described.

DESCRIPTION

FIG. 1 is a top perspective view of a lid;

FIG. 2 is a top plan view thereof;

FIG. 3 is a front elevational view thereof; and,

FIG. 4 is a right-side elevational view thereof.

The evenly dash broken lines in FIGS. 3 and 4 depict portions of the article and form no part of the claimed design. A rear elevational view is not shown because it is identical to the front elevational view shown in FIG. 3. A left side elevational view is not shown because it is identical to the right-side elevational view shown in FIG. 4.
